UNITED STATES PATENT OFFICE.

WALTER A. WOOD, OF HONESDALE, PENNSYLVANIA, ASSIGNOR TO T. B. CLARK & CO., OF SAME PLACE.

DESIGN FOR ORNAMENTATION OF GLASSWARE.

SPECIFICATION forming part of Design No. 21,466, dated April 12, 1892.

Application filed March 12, 1892. Serial No. 424,716. Term of patent 14 years.

To all whom it may concern:

Be it known that I, WALTER A. WOOD, of Honesdale, in the county of Wayne and State of Pennsylvania, have invented and produced 5 a new and original Design for the Ornamentation of Glassware, of which the following is a specification, and which is shown in the accompanying drawing.

In the drawing the figure is a plan view of 10 the outside of the glass dish formed according to my said design.

The main feature of my design consists of 15 arcuated grooves extending from margin to margin and intersecting each other at regular points. These arcuated grooves are marked *a a*. Between their intersecting ends are included spaces of lancet or inverted pointed arched form, (marked *b*.) Included in the center is a six-sided space, (marked *c*.) 20 The ornamentation subordinate to this main feature is as follows: In the center is a six-

pointed star, the points of which coincide with the crossings of the arcuated grooves. In the lancet-spaces are diverging grooves *d*, and in the spaces between the ends of the neighboring but non-crossing arcuated lines are radiating fan-shaped grooves with intermediate star and hatching ornamentation. The edge is formed in serrated arches springing from the ends of the arcuated grooves. 30

The design is applicable to other forms of glassware.

I claim—

The design for the ornamentation of glassware, as herein described and shown. 35

In testimony whereof I affix my signature in presence of two witnesses.

WALTER A. WOOD.
